By his Attorney John B. Seifert

UNITED STATES PATENT OFFICE.

GEORGE T. PEARSONS, OF NEW YORK, N. Y.

PORABLE FIRE-EXTINGUISHER.

1,243,759.

Specification of Letters Patent. Patented Oct. 23, 1917.

Application filed March 22, 1915. Serial No. 16,300.

To all whom it may concern:

Be it known that I, GEORGE T. PEARSONS, citizen of the United States of America, residing at New York city, county of New York, State of New York, have invented a new and useful Improvement in Portable Fire-Extinguishers, of which the following is a specification, reference being had to the accompanying drawing.

10 This invention relates to fire extinguisher in which a fire extinguishing liquid is contained in a tank or reservoir having a discharge outlet and having a generator therein to normally hold gas generating materials in a separated condition and free from the liquid in the tank, and it is the principal object of the invention to provide a fire extinguisher of this character in which the generated gas will act upon the fire extinguishing liquid in the tank to expel the same when the latter is held in various positions, whether in an upright or inverted position, or in a horizontal position, and provide means whereby the discharge outlet is in 15 communication with the liquid in the lowermost part of the tank whatever the discharge position of the latter may be.

A further object of the invention relates to a generator to normally hold gas generating materials in a separated non-reactive condition with means operable from the exterior of the tank to cause said materials to admix or combine and to hold the reacting mixture free from the liquid in the tank, 20 but to permit it to pass into the tank to act upon the liquid therein to expel the same no matter in what position the tank may be held.

Another object of the invention is to provide improved means in extinguishers of this character in which the discharge outlet for the tank has a pair of intakes constructed to rotate about an axis centrally of the tank whereby the outlet will be connected 25 at all times, and no matter in what position it may be held, with the liquid in the lowermost part of the tank, and means to automatically cut off one of said intakes when the other is in communication with the 30 outlet.

In the drawing accompanying and forming a part of this specification Figure 1 is

a sectional side elevation of a fire extinguisher embodying my invention. Fig. 2 is a sectional detail of the closure plug. Fig. 55 3 is a sectional detail of a valve to normally seal the generator from the tank; and Fig. 4 is a sectional detail to show the manner of supporting the generator and the closing cover therefor. 60

In carrying out the invention I provide a tank or reservoir to contain suitable fire extinguishing liquid, said tank consisting of a tubular portion 1 and a bottom 2 to also serve as a supporting base, and a top 3 having a central opening with an internal and external screw threaded flanged member 8 extending into the tank. The top has a discharge opening 4 in which engages a coupling 5, in the present instance a valve coupling, and to which may be connected the usual flexible hose (not shown). The tank is filled through an opening 6 in the top which is normally closed by a screw threaded cap or plug 7. 70

Secured to the external screw threads of the flange 8 is a receptacle 9 which is in the nature of a gas generating chamber, and adapted to carry a suitable gas generating material such as bicarbonate of soda in a suitable form, said receptacle having a pair of discharge outlets 10, 11 leading to the tank to which are connected valve chambers 12, 12' having outwardly opening and inwardly closing check valves, whereby the material 80 and the reacting gas in the receptacle 9 are free from the liquid in the tank, the pressure of the gases in the receptacle 9 unseating the valves to automatically connect the receptacle with the tank and permit the discharge of the generated gas to the latter. 85

Each of the valve chambers 12, 12' has a projecting portion 13, 13' adapted to align with openings in the top of the tank, and such projecting portions having a perforation closed by a cap or plug 14, 14', from the exterior of the tank, said plugs also serving to seal the openings in the top of the tank through which the plugs pass. By this means access may be had to the valves from 95 the exterior of the tank for cleaning or otherwise. The intake to the valve chamber 12' is directly at the top of the receptacle, whereas the intake to the valve chamber 12 100

is adjacent the bottom of the receptacle by connecting a tube 15 thereto and for a purpose to be hereinafter described.

A reacting mixture to produce gas may 5 consist of the bicarbonate of soda in the receptacle 9 and sulfuric or hydrochloric acid. However, these materials must be maintained in a separated condition until such 10 time as it is desired to utilize the extinguisher. For this purpose I provide for such other gas producing agent a second receptacle 16 of non-corrodible material, and said receptacle may be of the form shown 15 in the drawing having a neck constituted to have screw threaded connection with a cover or closure 17 for the opening in the top of the tank and by which cover said receptacle is carried. This cover has screw threaded connection with the internal 20 threads of the flange 8 and has a portion to overlap the top and between which overlapping portion and the top a suitable packing ring may be interposed. By connecting receptacle 16 to the cover in the manner 25 shown the gas generating material carried thereby is sealed from the material in the receptacle 9 with the result that there will be no gradual evolution of gases which 30 would in time materially affect the gas producing quality of the materials.

To release the acid from the receptacle 16 to permit it to admix with the material in the receptacle 9, the former has a weakened portion, in the present instance shown centrally thereof as at 18, and means are provided to rupture or break the receptacle 35 from the exterior of the tank. For this purpose the cover 17 has an opening in line with the opening in the neck of the receptacle 16 with screw threads preferably of a 40 steep pitch. Screw threaded into said opening and passing into the receptacle is a stem or plunger 19 of suitable material with its lower end adjacent the bottom of the receptacle, and which end may have a head or 45 the like connected thereto. To make the opening in the cover air tight there is provided a stuffing box, as at 21 through which the plunger passes. A hand grip 22 is fixed 50 to the outer end of the plunger or stem to rotate the same. It is obvious that by rotating the stem and forcing it against the bottom it will cause the receptacle to separate at the weakened portion 18 and permit the 55 contents to drop into the generator 9 and admix with the gas generating material therein and instantaneously generate gas. To assure the emptying of the contents from the separated bottom of the receptacle 16 one end of a chain or the like is connected 60 to the cover 17 and the other end to the bottom of the receptacle.

As gas is generated when the extinguisher is in an upright position the pressure of the

gas will unseat the valve 12' and pass into 65 the tank 1, the force or pressure of the gas exerted on the liquid in the tank expels said liquid through the discharge outlet 4. Should the generator be inverted and the gas generating materials assume a position adjacent 70 the cover 17 said materials will close the outlet 12' and prevent the expelling of the generating gas through said outlet into the tank. To permit the generated gas to enter the tank from the generator in such position 75 of the extinguisher the outlet 12 having the intake tube 15 extending to adjacent the bottom of the generator is provided. It will thus be obvious that when the extinguisher is used in upright position the generated gas 80 will pass through the outlet 12' the discharge of the gas through outlet 12 being prevented by the gas generating materials, and when the extinguisher is inverted the discharge of the gas is prevented through 85 the outlet 12' by such materials. As the receptacle 16 is broken the acid contained therein coming in contact with the soda does not immediately penetrate and pass through 90 the soda, but as it comes in contact with the upper surface or layer of the soda it instantly forms a saturated layer at the upper portion of the soda and evolves gas. This gas pressure taking the course of least resistance will pass through the outlet 12', as 95 assuming that the extinguisher is in upright position. The acid gradually passes through the soda until it forms with the whole of the soda, or that portion which has not already been expended, a saturated cake, but at no 100 time is there a liquid which could be forced through the outlets of the generator. After the soda is saturated with the acid it is quite possible that gas may also be discharged through the outlet 12 but this is not detri- 105 mental to the operation of the extinguisher. The provision of the two outlets from the generator, the one 12 with its intake adjacent the bottom of the generator, permits of the easy and ready exit of the gas from the 110 generator to the tank or reservoir during the early stages of the gas production, whether the extinguisher is held in upright or inverted position. To prevent choking up 115 of the outlets 12, 12' by the gas generating materials the generator has a screen 37 adjacent the bottom but at a point above the inlet to the intake tube 15, and a screen 38 at the top adjacent the outlet 12' and upon which screens the gas generating materials are sup- 120 ported in the various positions of the extinguisher. To connect the discharge outlet of the reservoir at all times with the liquid in the lowermost part of the reservoir and permit of the discharge of the 125 liquid from the tank in various positions thereof, as in an upright, inverted or horizontal position, the outlet 4 has a pair of

intakes 23, 24, the inlet of intake 23 being located at the upper end of the tank and adjacent the side and the inlet of intake 24 at the bottom adjacent the side. The intakes are adapted to have rotation about an axis centrally of the tank whereby they will assume a position in the lowermost part of the reservoir or tank when held in a horizontal position. For this purpose a tube 25 is connected at one end to the discharge outlet and at the other end with a tubular member 26 supported on the under side of the bottom of the generator 9, and in which is rotatably mounted one end of a pipe 26', the other end of said pipe being closed and rotatably supported in the bottom of the tank as at 27. The intakes 23 and 24 are in the form of tubes connected to the pipe 26' one adjacent the upper end of the pipe 20 with its inlet end to lie adjacent the side and one end of the tank and the other adjacent the lower end of the pipe with its inlet adjacent the side and the end of the tank as clearly shown in the drawing.

25 To cause the pipe 26' with the intakes to rotate so that the latter will assume a position at all times in the lowermost part of the tank there is connected to the pipe a weight 28.

30 To cut off one of the intakes when the other is in communication with the outlet 4 so that only one intake will be connected to the outlet, as for instance the intake 24 when the extinguisher is in an upright position as shown in the drawing to prevent of the discharge of the expelling gas or agent, I provide valve mechanism comprising a tube 29 slidably mounted in the pipe 26' having a series of circumferentially disposed ports 30 and 31 in line with annular recesses in the tube. To impart sliding movement to said tube the weight 28 is pivotally connected at 32 to a bracket 33 fixed to the pipe 26', a pin 34 fixed in the pipe 40 29 passing through a longitudinal slot 36 in the pipe 26' and engaging in a transverse slot 35 in the weight carrying arm. When the extinguisher is in an upright position as shown in the drawing the intake 24 will 45 be connected through the ports 31 with the discharge outlet tube 25 through the tube 29, and the ports 30 will be in position to be closed by the pipe 26' and the tube 29 will cut off the intake tube 23 from the discharge outlet tube 25. It will be obvious 50 that when the extinguisher is in an upright position or in a slightly inclined position, or in a horizontal position, intake 24 will be in operative connection with the discharge outlet and that such intake will be maintained by the weight 28 in the liquid in the tank in the lowermost part thereof. Should the extinguisher be inverted the weight will slide the tube 29 so that the ports 30 will

be in connection with the intake 23 and connect the latter to the discharge outlet tube 25, access to the discharge outlet by the intake 24 being cut off by the tube 29. By the pin and slot connection 34, 35, and 36 with the pipes 26' and 29, said pipes will be 55 simultaneously rotated.

Should it be desired to stop the discharge of the liquid from the tank while the gas is still being generated in the receptacle 9 means are provided to relieve the gas pressures in the tank and thereby prevent the expelling of the liquid therefrom. For this purpose the plug 7 for the filler opening 6 has a central perforation 40 with which lateral perforations 41 in the plug communicate. When the plug is seated these openings are closed by the walls of the filler opening and the lateral perforations are so arranged that by giving the plug a slight rotation they will be uncovered and the gas 85 will be permitted to escape therethrough.

Having thus described my invention, I claim:

1. In a fire extinguisher, the combination with a tank to contain fire extinguishing liquid having a discharge outlet, of a generator in said tank to hold gas generating materials in a separated condition and having an outlet into the tank, and a check valve in said outlet to normally disconnect the generator from the tank, the casing of said valve having a lateral opening adapted to be closed by means from the exterior of the tank passing through an opening in the tank, substantially as and for the purpose 100 specified.

2. In a fire extinguisher, the combination with a tank to contain fire extinguishing liquid having a discharge outlet, of a generator in said tank to hold gas generating materials in a separated condition and having an outlet into the tank; a check valve for said outlet to control the discharge of the gas from the generator to the tank, the casing of said valve having a lateral projecting portion with an opening therein adapted to be placed in line with an opening in the reservoir whereby access may be had to the interior of the valve from the exterior of the reservoir; and a removable 115 closure for the opening in said projecting portion to be applied thereto from the exterior of the tank, substantially as and for the purpose specified.

3. In a fire extinguisher, the combination with a tank to contain fire extinguishing liquid having a discharge outlet, of a generator in said tank suspended from the top thereof to hold gas generating materials in a separated condition; a pair of outlets adjacent the top of the generator to the tank, one of said outlets having an inlet in the generator adjacent the top thereof and the

- other an inlet adjacent the bottom of the generator to permit of the passage of the gas from the generator to the tank when the tank is held in either an upright or inverted position, substantially as and for the purpose specified.
4. In a fire extinguisher, the combination with a tank to contain fire extinguishing liquid having a discharge outlet, of a generator in said tank suspended from the top thereof to hold gas generating materials in a separated condition and having a pair of outlets adjacent the top to the tank, one of said outlets leading from the bottom of the generator to permit of the passage of the gas from the generator to the tank when in an inverted position and the other leading from the top; and outwardly opening check valves to control the passage of the gases from the generator to the tank; substantially as and for the purpose specified.
5. In a fire extinguisher, the combination with a tank to contain fire extinguishing liquid having a discharge outlet, of a generator in said tank suspended from the top thereof to hold gas generating materials in a separated condition and having a pair of outlets adjacent the top of the tank, one of said outlets leading from the bottom of the generator to permit the passage of the gas from the generator to the tank when in an inverted position and the other leading from the top; screens in said generator, adjacent each outlet; check valves for said outlets, the chambers of which valves each having a perforated projecting portion in line with openings in the tank; and caps to close said perforations from outside of the tank, substantially as and for the purpose specified.
6. In a fire extinguisher the combination with a tank to contain fire extinguishing liquid having a discharge outlet, of a generator therein suspended from the top thereof to hold gas generating materials in a separated condition and having a pair of outlets to the tank adjacent the top, the intake of one of said outlets being adjacent the top of the generator and the intake of the other outlet adjacent the bottom; and an outwardly opening and inwardly closing check valve in each outlet to control the passage of the gases from the generator to the tank, substantially as and for the purpose specified.
7. In a fire extinguisher, the combination with a tank to contain fire extinguishing liquid, of a generator in said tank to hold gas generating materials in a separated condition and free from the liquid in the tank and having an outlet leading to the tank; a discharge outlet for the tank having a pair of intakes, one adjacent to each end of the tank; and means to cut off one of the intakes when the other is in communication with the discharge outlet, substantially as and for the purpose specified.
8. In a fire extinguisher, the combination with a tank to contain fire extinguishing liquid, and a generator therein to hold gas generating materials in a separated condition and free from the liquid in the tank and having an outlet leading to the tank, of a discharge outlet for the tank, and a pair of intakes for said outlet, one adjacent each end of the tank and the side thereof, and both intakes concomitantly rotatable about an axis centrally of the tank, substantially as and for the purpose specified.
9. In a fire extinguisher, the combination with a tank to contain fire extinguishing liquid, and a generator therein to hold gas generating materials in a separated condition and free from the liquid in the tank and having an outlet leading to the tank, of a discharge outlet for the tank, and a pair of intakes for said outlet, one adjacent each end of the tank and the side thereof, and both intakes concomitantly rotatable about an axis centrally of the tank, substantially as and for the purpose specified.
10. In a fire extinguisher, the combination with a tank to contain fire extinguishing liquid and having an outlet, and a generator therein to hold gas generating materials in a separated condition and free from the liquid in the tank; a pair of intakes for said outlet, one adjacent each end of the tank and the side thereof, and both intakes concomitantly rotatable about an axis centrally of the tank, and means to cause said intakes to rotate and assume a position below the axis of rotation whereby liquid may be discharged from the tank in various positions thereof, substantially as and for the purpose specified.
11. In a fire extinguisher, the combination with a tank to contain fire extinguishing liquid, of a gas generator therein to hold gas generating materials in a separated condition and free from the liquid in the tank; means exterior of the tank to cause said materials to admix; a pair of valve discharge outlets adjacent the top of said generator leading to the tank and the intake of one of said outlets being adjacent the bottom of the generator whereby the gas may be discharged to the tank in various positions thereof; a discharge outlet for the tank; and a pair of intakes for said outlet, one adjacent each end of the tank and the side thereof, and both intakes concomitantly rotatable about an axis centrally of the tank, and means to cause said intakes to rotate and assume a position below the axis of rotation whereby liquid may be discharged from the tank in various positions thereof, substantially as and for the purpose specified.

tantly rotatable about an axis centrally of the tank whereby liquid may be discharged from the tank in various positions thereof; and valve mechanism to cut off one of the 5 intakes when the other intake is in communication with the tank outlet, substantially as and for the purpose specified.

In testimony whereof, the said GEORGE T. PEARSONS has signed his name to this spec-

ification in the presence of three subscriber- 10 ing witnesses, this Nineteenth day of March 1915.
